UNITED STATES PATENT OFFICE

2,536,715

TOY TYPEWRITER

Samuel I. Berger, Newark, N. J.

Application February 27, 1947, Serial No. 731,318

9 Claims. (Cl. 197—47)

1

It is among the objects of my present invention to provide a toy typewriter which has all the advantages of that of my prior applications Serial No. 658,318, filed March 29, 1946 and since issued as Patent No. 2,486,702, dated November 1, 1949, and Serial No. 724,043, filed January 24, 1947 and since issued as Patent No. 2,458,137, dated January 4, 1949, and my previous issued Patent No. 2,398,765, dated April 23, 1946, including the use substantially solely of sheet metal and rod stock to simulate the appearance of a genuine portable typewriter by a greatly simplified construction.

In the accompanying drawings in which is shown one of various possible embodiments of the several features of the invention,

Fig. 1 is a plan view of a toy typewriter according to the present invention, showing its general appearance with the simulated keyboard and associated structure in place thereon,

Fig. 2 is a transverse sectional view thereof taken along line 2—2 of Fig. 1,

Fig. 3 is a view similar to Fig. 2, with the key lever depressed, showing the type wheel in typing position, and

Fig. 4 is a sectional detail view of the platen structure on a larger scale taken along line 4—4 of Fig. 1.

Since the construction in its general outline follows closely that of the applications and patent above identified, only so much of the construction has been shown as is needed to afford a clear understanding of the present improvements, and the general description will be correspondingly brief.

Referring now to the drawings, as shown in Fig. 1, the toy typewriter simulates the appearance of a modern portable typewriter presenting as it does a base 11 having a simulated standard keyboard 12 thereon. This keyboard may be directly printed on the platform 15 or printed on a rectangular sheet metal plate which is affixed to the surface of the platform. A standard at the center of the base supports the operating mechanism of the device and a platen structure 14 is mounted on the base to the rear of the standard.

Base 11 comprises a rectangular platform 15 having a downwardly turned skirt 16 on the periphery thereof. Affixed to the rear of the platform 15 at each corner thereof and depending therefrom is a supporting leg comprising a U-shaped strip of sheet metal, presenting a cross piece 17 and upstanding side walls 17. The upper edges of side walls 17 are beveled as at 18

and are connected by tines (not shown) with the platform 15 to support the latter obliquely, as shown.

A key lever 25 is pivoted on an axle 26, the latter being journalled in side walls 20 rising from the lateral edges of a rectangular bracket 13 affixed to the platform by means of downwardly turned tines 23 integral with each corner of the bracket and which pass through the platform. Each of the arms 27 of the key lever 25 is pivoted to a link 28, the upper end of said link being pivoted by means of an axle 29 to the obliquely extending arms 30 of a substantially U-shaped sheet metal carriage 31. The end 32 of each of said oblique arms 30 is pivoted as at 32 to upstanding ears 21 rising from the rear end of each side of the bracket 13.

Depending from carriage 31 is a U-shaped bracket 33, the arms of the bracket being affixed to the carriage as at 34. A type wheel 35 having on its periphery the type heads comprising the sequence of letters and numerals, is affixed on a substantially upright axle 36 journalled in bearing openings 37 and 38 in bracket 33 and carriage 31, respectively, and protruding therefrom, the axle in position of rest being at substantially right angles to platform 15.

The type wheel 35 is adjustable to a selected setting by means of a rotatable cup shaped dial 39 which bears the sequence of letters and numerals on its upper surface. Dial 39 has a hub 40 unitary therewith on its undersurface and it is affixed to the upper end of axle 36 protruding from carriage 31 by means of a set screw 41 in said hub, a notch 42 on the periphery of said dial affording convenient access to said set screw. Dial 39 preferably has a knob 45 unitary therewith on the surface thereof, the peripheries of said dial and said knob being serrated as at 46 to facilitate gripping thereof. A coil spring 43 surrounding said axle 36 between the type wheel and the carriage serves to take up any looseness and retain the axle in position between carriage 31 and bracket 33.

Ratchet means which includes a horizontal ratchet wheel 48 interposed between bracket 33 and type wheel 35 and affixed to type wheel axle 36 by a set screw 49 is preferably provided to step the type wheel around in effective setting thereof by the turning of dial knob 45. As this mechanism has been fully described in my above identified applications and patent, it will not be more fully described herein. A pointer 47 which is struck out from carriage 31 is positioned so

as to be near the periphery of said dial 39 to indicate the selected setting thereof.

For applying ink to the type head, an ink retaining absorbent roller 50 which is itself conventional is preferably provided. This roller is mounted on a bail 51 integral with and extending outward from the midsection of the cross arms of a substantially U-shaped bracket 52, the arms 53 and 54 of which are pivoted to carriage 31, preferably by means of hollow rivets, as at 55. Arm 54 is extended as at 56 and is connected by pitman 57 to side wall 20 of bracket 13 for the purpose hereinafter described.

The escapement structure is quite similar to that of my above identified issued patent and need therefore be but briefly described. The escapement box 58 is conventional and its interior parts are not shown. Its protruding pawls 59 coact with an indented rack 60 on the base of the platen structure. The escapement is operated from a cam plate 61 freely rotatable about the axle 26 of the key lever 25 and connected by a wire link 62 hooked as at 63 to plate 61 at one end and to the mechanism in the escapement box 58 at the other. A link 64 pivoted at one end to axle 29 and having a stud 65 at its other end riding in an arcuate slot 66 in the cam plate causes the latter to be pivoted by the depression stroke of the key lever 25, thereby to pull link 62 forward for the escapement action.

The spacer key 67 is formed as a unitary part of a substantially rectangular axle rod 68 journaled in side walls 20 of the bracket 13. One end of axle rod 68 extending beyond side wall 20 has an upwardly turned portion 69 which in turn has a substantially right angled extension 70 extending toward the front of platform 15. The end of extension 70 is looped as at 71 and a cup shaped disc 72 is affixed thereto as by force fit.

Affixed to said axle rod 68 is a substantially U-shaped pitman 73 having substantially rectangular holes in each arm 74 thereof which encompass said axle rod 68. One of the arms 74 of pitman 73 has an extension 75 unitary therewith having a laterally extending lug 76 thereon which is pivoted in a slot 77 in cam plate 61, riding idly therein when key lever 25 is depressed and actuating the escapement mechanism through link 62 when spacer key 67 is depressed.

To enclose the operating mechanism supported by side walls 20 of bracket 13, a substantially cylindrically curved sheet or cover piece 78 is provided which is affixed to the base of the bracket 13. Cover 78 has a slot 79 at the rear thereof through which link 62 and link 64 extend. Key lever 25 has a panel 80 unitary therewith and extending upwardly therefrom, as shown in Figs. 2 and 3. When key lever 25 is at rest position, panel 80 will enclose the type wheel and its associated mechanism. Panel 80 has an inwardly turned lip 80' which abuts against a downwardly turned skirt 31' on the front of carriage 31 when the latter has pivoted to rest position under the influence of gravity after key lever 25 has been released. Lip 80' and skirt 31' serve as a stop to properly position the carriage in rest position and prevent bracket 33, which depends from carriage 31, from hitting cover 78 which is of relatively thin sheet metal, and possibly denting said cover and jamming the mechanism thereunder.

The platen structure, preferably of sheet metal, 75

comprises a rectangular mounting plate 81 having a channel 82 at the bottom thereof. The edges of plate 81 are reversely turned as at 83 to form flanges 84 and 85 with walls 86 and 87 unitary therewith and rising therefrom. The front wall 86 of plate 81 has a plurality of parallel vertical slots or indentations 88 therein forming a rack 60.

Extending laterally inward from the upper edge of wall 81 is a sheet metal support strip 89. Affixed to said support strip 89 along the free edge thereof and extending substantially laterally therefrom to the front wall 86 of plate 81 is a sheet metal index strip 90 which is bent upwardly at its free edge so as to form a front wall 91 substantially flush with wall 86 of plate 81 and extending upwardly therefrom. The face of wall 91 has indicia thereon simulating those of a standard typewriter.

Affixed to the ends of said rectangular plate 81 are sheet metal end plates 92 desirably flanged as at 93 and embracing the extremities of sheet metal index strip 90, and a cylindrically curved sheet metal plate 94 which simulates a platen and which has its forward edge 94' positioned behind the wall 91 of the index strip 90. Plate 94 has a groove 95 therein on the face thereof immediately above the edge of front wall 91 of the index strip 90 and parallel thereto. In said groove 95 is a strip 96 desirably of yielding rubber of suitable hardness which takes the impact of the type.

To simulate the rotation of the platen and paper feed, a rectangular shaft 97 is provided which bears in ears 98 extending laterally inward from the ends of the index strip 90 and in end plate 92. Shaft 97 extends axially through the platen structure and has knobs 98 at the extremities thereof.

Shaft 97 mounts a pair of rubber rollers 99 exposed through corresponding slots 100 in front wall 91 of the index strip 90, and coacts with corresponding rubber rollers 101 near the ends of a longitudinal rod 102 bearing in outstanding tongues 103 on the index strip 90. To retain rollers 99 and 101 in close contact, a spring arm 102' is provided, anchored at one end to the support strip 89 as at 89', and the free end 102' of which passes through a slot 86' in front wall 86.

To simulate the ratcheting action in the platen movement, a radially crimped metal washer 104 about rectangular shaft 97 rides on radiating teeth 104' on the exterior of end plates 92 against the resistance of a strong leaf spring 105 anchored at 106 to the extension of said end plate 92 and engaging the crimped washer.

Preferably the platen is also provided with a paper bail 107 of metal rod longitudinally of the platen with arms 108 extending between the ends of the platen and the operating knobs 98 and having a looped portion at the ends thereof through which the shaft 97 extends. The bail is movable about the shaft in the insertion of the paper against the resistance of a coil spring 109 anchored at one end to the exterior of the platen end plate 92 and at the other near the outer end of the bail arm.

The platen is slidably mounted in a channelled guide plate 110 which is affixed to the platform 15 near the rear edge thereof. The edges of the guide plate are inwardly turned as at 111 and coact with flanges 84 and 85 on the platen mounting plate 81 to slidably retain the latter on the platform. Guide plate 110 has a plurality of

ridges 112 unitary therewith and extending longitudinally thereof to serve as guide rails for the mounting plate.

As many changes could be made in the above construction and many apparently widely different embodiments of this invention could be made without departing from the scope of the claims, it is intended that all matter contained in the above description or shown in the accompanying drawings shall be interpreted as illustrative and not in a limiting sense.

Having thus described my invention, what I claim as new and desire to secure by Letters Patent of the United States is:

1. In a typewriter mechanism, the combination of a base, a rectangular platen guide plate having inwardly turned edges and affixed to said base at the rear thereof, a rectangular mounting plate having reversely turned edges forming flanges at each side thereof which coat with the inwardly turned edges of said guide plate for sliding mount thereof on said guide plate, a substantially cylindrically curved platen affixed to said mounting plate, a carriage pivoted on said base, a rotatable type wheel bearing in said carriage, an escapement mechanism affixed to said base and coacting with said mounting plate intermittently to step the latter along said guide plate, and means for rocking said carriage to imprint the selected type against said platen.

2. In a typewriter mechanism, the combination of a base, a rectangular platen guide plate affixed to the base at the rear thereof and having inwardly turned edges and longitudinal guide ridges on the surface thereof, a rectangular mounting plate having a longitudinal channel on the bottom thereof and reversely turned edges forming flanges at each side thereof which coat with said inwardly turned edges of said guide plate for sliding mount thereof on said guide plate, a substantially curved platen affixed to said mounting plate, a substantially U-shaped bracket affixed to said base, a carriage pivoted on said bracket, a rotatable type wheel bearing in said carriage, means for rocking said carriage on said bracket from rest to typing position, said means comprising a key lever pivoted to said bracket and having a panel unitary therewith and extending upwardly therefrom to conceal said type wheel when said carriage is in rest position, and a link connecting said key lever to said carriage for tilting the latter, escapement mechanism for said platen, means supported by said bracket for actuating said escapement mechanism, and a substantially cylindrically curved cover piece affixed to said bracket and enclosing said actuating means.

3. The combination set forth in claim 2 in which the means to actuate said escapement mechanism comprises a rectangular bar journaled in said bracket and extending therefrom on one edge thereof, a spacer key unitary with said bar for actuating the latter, an axle journaled in said bracket, a cam plate idly mounted on said axle, said cam plate having a slot therein, a link interconnecting said cam plate and said escapement mechanism and a substantially U-shaped bracket affixed to said rectangular bar and having an arm extending therefrom, said arm having a portion extending into the slot in said cam plate to rotate the latter when said spacer key is depressed to actuate the escapement mechanism.

4. In a typewriter mechanism, the combination of a base, a rectangular guide plate affixed to

said base at the rear thereof having inwardly turned edges and guide ridges on the surface thereof, a rectangular mounting plate having a longitudinal channel on the bottom thereof to ride on said guide ridges, and reversely turned edges forming flanges on each side thereof with walls extending upwardly therefrom and unitary therewith, one of said walls having a plurality of parallel vertical slots on the face thereof, said flanges coacting with said inwardly turned edges of said guide plate for slidable movement of said mounting plate therealong, a curved platen affixed to said mounting plate, a carriage pivoted on said base, a rotatable type wheel bearing in said carriage, and an escapement mechanism affixed to said base and coacting with the slots in the wall of said mounting plate intermittently to step the latter along said guide plate.

5. In a typewriter mechanism, the combination of a base, a rectangular guide plate affixed to said base at the rear thereof and having inwardly turned edges and longitudinal ridges on the surface thereof, a rectangular mounting plate having a longitudinal channel on the bottom thereof to ride on said guide ridges, and reversely turned edges forming flanges at each side thereof with walls extending upwardly therefrom, one of said walls having a plurality of parallel vertical slots on the face thereof, said flanges coacting with said inwardly turned edges of said guide plate to slidably mount said mounting plate on said guide plate, a substantially cylindrically curved platen affixed to said mounting plate and having a fixed yielding impact strip at the front thereof, a carriage pivoted on said base, a rotatable type wheel bearing in said carriage, an escapement mechanism affixed to said base and coacting with the slots in the wall of said mounting plate to intermittently step the latter along said guide plate, and means for rocking said carriage to imprint the selected type against the yielding strip on said platen.

6. As an article of manufacture, a platen structure for a toy typewriter, said platen structure comprising a rectangular mounting plate having a longitudinal channel on the bottom thereof and reversely turned edges forming flanges at each side thereof with walls extending upwardly therefrom, and a substantially cylindrically curved platen affixed to said mounting plate, said platen having a fixed yielding impact strip at the front thereof.

7. In a typewriting mechanism, the combination of a base, a platen mounted on said base, a bracket affixed to said base, a substantially U-shaped carriage pivoted on said bracket and having a downwardly turned skirt on the front edge thereof, a type wheel rotatably mounted on said carriage, and means for rocking said carriage on said bracket from rest to typing position to bring said type wheel in contact with said platen, said means comprising a key lever pivoted to said bracket and having a panel unitary therewith and extending upwardly therefrom, and a link connecting said key lever to said carriage for tilting the latter, said panel having an inwardly turned lip at the upper edge thereof which abuts against the downwardly turned skirt on said carriage to limit the movement of the latter as it pivots to rest position.

8. In a typewriting mechanism, the combination of a base, a platen mounted on said base, a bracket affixed to said base, a carriage pivoted on said bracket, a substantially upright axle bearing in said carriage and having affixed there-

on in coaxial relation therewith, a ratchet wheel, a type wheel and a dial knob, and means for rocking said carriage on said bracket from rest to typing position, said means comprising a key lever pivoted to said bracket and having a panel unitary therewith and extending upwardly therefrom to conceal said type wheel and said ratchet wheel when said carriage is in rest position, and a link connecting said key lever to said carriage for tilting the latter, said panel having an inwardly turned lip at the upper edge thereof which abuts against the downwardly turned skirt on said carriage to limit the movement of the latter as it pivots to rest position.

9. In a typewriting mechanism, the combination of a base, a platen slidably mounted on said base, a bracket affixed to said base, a substantially U-shaped carriage pivoted on said bracket and having a downwardly turned skirt on the front edge thereof, a substantially upright axle bearing in said carriage and having affixed thereto in coaxial relation therewith a ratchet wheel, a type wheel and a dial knob, means for rocking said carriage on said bracket from rest to typing position, said means comprising a key lever pivoted to said bracket and having a panel unitary therewith and extending upwardly therefrom to conceal said type wheel and said ratchet wheel.

when said carriage is in rest position, and a link connecting said key lever to said carriage for tilting the latter, said panel having an inwardly turned lip at the upper edge thereof which abuts against the downwardly turned skirt on said carriage to limit the movement of the latter as it pivots to rest position, an escapement mechanism for said platen, means supported by said bracket for actuating said escapement mechanism, and a substantially cylindrically curved cover piece affixed to said bracket and enclosing said actuating means.
